BOBBIN HOLDER

Chase L. Leavitt, Los Angeles, Calif., assignor to Reynolds Industries, Inc., Santa Monica, Calif., a corporation of California

Filed Feb. 23, 1966, Ser. No. 1,155

Term of patent 14 years

(Cl. D3—19)

FIG. 1 is a perspective view of a bobbin holder with the cover removed, showing my new design;

FIG. 2 is a top plan view with the cover on;

FIG. 3 is a side elevation view;

FIG. 4 is an end elevational view; and

FIG. 5 is a sectional view taken on the line 5—5 in FIGURE 2.

I claim:

The ornamental design for a bobbin holder, substantially as shown and described.
